(57) **CLAIM**

The ornamental design for a finger-wearable oral hygiene device, as shown and described.

DESCRIPTION

FIG. 1 is a front perspective view of a finger-wearable oral hygiene device having extensions extending from an outer surface of a body, according to the invention;

FIG. 2 is a rear perspective view thereof showing an opening;

FIG. 3 is another front perspective thereof;

FIG. 4 is another rear perspective view thereof; and,

FIG. 5 is a profile view thereof.

The broken lines in the drawing figures illustrate environmental structure and form no part of the claimed design.

1 Claim, 5 Drawing Sheets
